US00D723534S

(12) **United States Design Patent**
Kim et al.

(10) **Patent No.:** **US D723,534 S**
(45) **Date of Patent:** ** *Mar. 3, 2015

(54) **CASE FOR ELECTRONIC DEVICE**

(71) Applicant: **Samsung Electronics Co., Ltd.**,
Suwon-si (KR)

(72) Inventors: **Yoon-Young Kim**, Seongnam-Si (KR);
Won-Kyu Sung, Seongnam-Si (KR)

(73) Assignee: **Samsung Electronics Co., Ltd.**,
Suwon-si (KR)

(*) Notice: This patent is subject to a terminal disclaimer.

(**) Term: **14 Years**

(21) Appl. No.: **29/456,473**

(22) Filed: **May 31, 2013**

Related U.S. Application Data

(63) Continuation of application No. 29/448,600, filed on Mar. 13, 2013.

(57) **CLAIM**

The ornamental design for a case for electronic device, as shown and described.

DESCRIPTION

FIG. 1 is a perspective view of a case for electronic device, showing our new design;

FIG. 2 is a front view thereof;

FIG. 3 is a rear view thereof;

FIG. 4 is a left-side view thereof;

FIG. 5 is a right-side view thereof;

FIG. 6 is a top plan view thereof;

FIG. 7 is a bottom plan view thereof;

FIG. 8 is an open perspective view thereof; and,

FIG. 9 is an open-rear perspective view thereof.

In the drawings, the broken lines depict unclaimed environment and form no part of the claimed design.

1 Claim, 7 Drawing Sheets
